UNITED STATES PATENT OFFICE.

OTTO J. GROEHN, OF DETROIT, MICHIGAN, ASSIGNOR TO CLAYTON & LAMBERT MANUFACTURING COMPANY, OF DETROIT, MICHIGAN, A CORPORATION OF MICHIGAN.

TORCH-BURNER CONSTRUCTION.

Application filed November 30, 1921. Serial No. 518,882.

To all whom it may concern:

Be it known that I, OTTO J. GROEHN, a citizen of the United States of America, residing at Detroit, in the county of Wayne and State of Michigan, have invented certain new and useful Improvements in Torch-Burner Constructions, of which the following is a specification, reference being had therein to the accompanying drawings.

This invention relates to burners and refers more particularly to oil burners or the like of that class which are used in connection with blow torches or similar devices. It is one of the objects of the invention to provide an improved construction in which the burner orifice is prevented from clogging and more particularly to provide a means for cleaning the discharge orifice or nozzle of the burner so that it can be readily maintained in operative condition. An essential feature of the invention is to so construct and arrange this clean-out member that it is readily available for use but is so constructed and arranged that it cannot be jammed against the discharge orifice of the burner nor can it be withdrawn so as to permit the flame to back-fire or the gas to escape from the rear of the clean-out member.

The invention contemplates the novel arrangement wherein the control valve is located at a position distant from the discharge orifice and the cleaning nozzle arranged adjacent the final discharge orifice but primarily adapted to form a clean-out member and not a shut-off valve. In case the clean-out member is adjusted by a screw thread it is of course possible to exert a tremendous amount of force on the seat should the clean-out member be free to move forward to an unlimited extent. In the present novel construction I not only limit the forward movement of the clean-out member but also limit the rear movement. Other features of the invention reside in such arrangements and combinations of parts as will more fully hereinafter appear.

In the drawings:

Fig. 1 is a vertical sectional view partly in elevation of a burner embodying my invention;

Fig. 2 is a sectional view taken on the line 2—2 of Fig. 1, and

Fig. 3 is an enlarged fragmentary sectional view showing a modified construction. 55

Describing in detail the particular embodiment of my invention shown in the drawings, A designates the tank of a blow torch and B the burner mounted thereon and secured to the tank by a suitable stem C. Fuel from the tank is fed to the burner upwardly through the tube or stem C and through the preheating chamber D which, because of the upward off-set arrangement of the tube D' compels the fuel 60 to pass adjacent the hot wall of the chamber E before reaching the valve seat F. The latter is controlled by a needle valve F' and when this valve is opened the fuel passes up through the passageway G to the 65 discharge orifice or outlet H.

As shown in detail in Fig. 1 this discharge orifice H is mounted in a removable member H' and the gas passing the discharge orifice H mixes with air through the ports I 75 and is burned in the combustion chamber E. Owing to the proximity of the outlet orifice H to the combustion chamber E it is advantageous to locate the control valve F' at a point remote from this discharge orifice but some means must be provided to keep the orifice H open in case carbon or other matter should be deposited in the orifice. In place of using a separate valve at this point I preferably employ a clean-out 80 needle J carried by a stem J' and adapted to be projected into and through the orifice H as desired. The stem J is screw-threaded at J² in a rearwardly extending nipple K and is controlled by a hand-wheel J³ 85 mounted on the end of the stem J' and located preferably above the hand-wheel F² which is mounted on the stem F¹ which carries the needle valve F'. In order to limit the forward movement of this clean-out 90 member the stem J' is provided with an enlargement L which upon the extreme forward movement of the stem J' will strike against the abutment L' while the outward movement of the stem J' is limited by the 95 enlargement L striking against the annular shoulder or abutment portion L². It will

be noticed that the abutment L' is carried by the collar M which serves to clamp the packing M' while the abutment L^2 is carried by a second collar or sleeve portion N . In this manner the parts are not only economically constructed but can be readily assembled and taken apart. Moreover this novel arrangement of parts prevents the injury to the discharge orifice H which is an important feature since it is necessary to maintain the relative proportion of the orifice to the other parts of the combustion chamber in order to secure the most efficient combustion of the fuel, while limiting the rearward movement prevents accidents which might arise owing to the operator inadvertently withdrawing the entire clean-out member and thus prevent the back-firing or burning of the fuel at a point other than the discharge orifice H .

The burner is provided with the usual drip cup O for priming or preheating the burner at the start and the usual hook Q for supporting the tool to be heated. In connection with this hook there is also provided the plug R which is tapered, and in shipping the burner the plug is forced tightly into place. As this plug is preferably formed of wood or other semi-compressible material it serves as a guard or protection to prevent the breaking of the hook. Prior to the adoption of this novel arrangement a large number of these hooks were broken in shipping the burner thus necessitating replacing or repairing large numbers of burners, whereas in the present construction this difficulty is entirely overcome.

In the particular construction shown in Fig. 3 the corresponding parts are identical with those shown in Fig. 1 with the exception that the clean-out member is not adjusted by a screw thread. In place of the screw threaded stem the clean-out member S in Fig. 3 is carried by a stem S' which has a rack S^2 engaged by a pinion T . The latter is rocked about its pivot T' by the arm T^2 . In this way the clean-out member can be quickly adjusted to perform its clean-out function and immediately return to its inoperative position. Suitable stops V and V' limit the forward and rearward movement of the clean-out member. This construction is advantageous not only because of the ease with which the clean-out member may be manipulated but it further serves to prevent the clean-out member from being jammed to its seat and even if it were permitted to reach the seat the expansion, due to heat, would not destroy the latter as the rack would simply move back and rock the pinion and arm T^2 .

What I claim as my invention is:

1. In a burner for blow torches or the like, the combination with a fuel passage having a discharge nozzle, of a nipple in rear of

said nozzle, a stem extending through said nipple and adjustable by a threaded engagement with the nipple toward and from said nozzle, a clean-out member carried by said stem and adapted to be reciprocated through said nozzle, an enlargement upon said stem, an abutment member detachably secured to said nipple engageable with said enlargement for limiting movement of said stem in one direction to protect the nozzle, and a second abutment member engaging the abutment member aforesaid and engageable with said enlargement for limiting movement of said stem in the opposite direction to prevent accidental complete withdrawal of the stem.

2. In a burner for blow torches, the combination with a fuel passage having a discharge orifice, of a nipple in alignment with the orifice, a stem threadedly adjustable in said nipple toward and away from said orifice, a clean out member carried by said stem adapted to be reciprocated through said orifice, a collar surrounding said nipple having a reduced portion fitting said stem, a collar surrounding the reduced portion of the collar aforesaid having an annular shoulder, and an enlargement on said stem alternately engageable with the outer end of the first collar and the annular shoulder of the second collar for limiting the movement of said stem toward and away from said orifice, and means remote from and independent of the clean out member and stem for controlling the flow of fuel through said passage.

3. In a burner for blow torches or the like, the combination with a fuel passage having a discharge nozzle, of a valve for controlling the passage of fuel to said nozzle, a stem adapted to be gradually and positively moved toward and away from said nozzle, a clean-out member carried by the stem and engageable with the nozzle, means carried by the stem at a point remote from the fuel passage for slidably housing the stem, and means cooperating therewith for limiting the movement of the stem toward the nozzle for preventing injury to the same and limiting movement of the stem away from the nozzle to prevent accidental complete withdrawal of the stem and consequent escape of the fuel from the said fuel passage through the said stem housing.

4. In a burner for blow torches or the like, the combination with fuel passage having a discharge nozzle of a valve for controlling the passage of fuel to said nozzle, a stem adapted to be gradually and positively moved toward and away from said nozzle, a clean-out member carried by the stem and engageable with the nozzle, means carried by the stem at a point remote from the fuel passage for slidably housing the stem, and means cooperating therewith for limiting

the movement of the stem toward the nozzle for preventing injury to the same and limiting movement of the stem away from the nozzle to prevent accidental complete

withdrawal of the stem and consequent escape of the fuel from the said fuel passage through the said stem housing, said

stem housing comprising a pair of telescoped abutment members each having a rearwardly extending portion embracing the ¹⁰ stem.

In testimony whereof I affix my signature.

OTTO J. GROEHN.
